UNITED STATES PATENT OFFICE.

FRITZ TIEMANN, OF BERLIN, GERMANY.

RECOVERY OF SUGAR FROM MOLASSES.

1,256,952.

Specification of Letters Patent. Patented Feb. 19, 1918.

No Drawing.

Application filed June 25, 1914. Serial No. 847,814.

To all whom it may concern:

Be it known that I, FRITZ TIEMANN, a subject of the German Emperor, residing at Berlin, W., 259 Kurfürstendamm, Germany, have invented certain new and useful Improvements in and Relating to the Recovery of Sugar from Molasses; and I do hereby declare the following to be a full, clear, and exact description of the invention, such as will enable others skilled in the art to which it appertains to make and use the same.

This invention relates to improvements in processes for recovering sugar from molasses of any origin.

It has not been possible to apply any of the existing processes for recovering crystallized sugar from the molasses resulting from the manufacture of beet sugar to molasses resulting from the manufacture of cane sugar, because the latter is much more impure than sugar beet molasses, and because the working expenses would be greater than the profits, as the required compounds of lime, strontia or baryta are too expensive.

It is a well known fact that certain substances dissolved in water may be recovered in a solid condition by adding certain other substances which are soluble in water, to the solution, the said added substances precipitating or causing the crystallization of the former substances from the solution.

Further it is a scientifically established fact that cane sugar may be expelled from an impure solution containing salts by adding levulose or dextrose (glucose) or a mixture of both kinds of sugar, *i. e.*, "invert sugar" to these saline sugar solutions.

Further it has already been proposed to utilize the aforementioned scientifically established property of dextrose for recovering crystallized sugar from molasses when working on a large commercial scale, so as to obtain an increased yield of sugar. The commercial dextrose available for this purpose, however, only contains about 60% of actual dextrose, whereas the remainder of about 40% consists of dextrins and the like, which, as is well known, have a very injurious and detrimental effect on the crystallizing out of the sugar, as they are instrumental in the production of molasses. As the dextrose is usually produced from starch flour and the like, it will be seen that according to this proposal a product must be added to the molasses which originates from quite a different industry.

This scientifically established property of invert sugar of expelling cane sugar from impure solutions is now to be utilized for recovering crystallized sugar from molasses which constitutes an impure saline solution of sugar and which already contains invert sugar. This is effected in accordance with the present invention, by adding artificially produced invert sugar to the molasses, the said artificially produced invert sugar being preferably produced in the manner herein-after described. The invert sugar produced from one portion of the molasses may thus be used for the separation (precipitation or crystallization) of the cane sugar contained in another portion of the molasses.

This recovered sugar may be separated in the form of sugar powder, in case molasses not containing crystals is treated, whereas if the molasses already contains sugar crystals, the sugar therein will be obtained in a crystallized form.

The latter result may be obtained by treating the molasses before its separation by centrifuging from the masse-cuite by adding artificially produced invert sugar thereto either after evaporation, or at any other stage before the said centrifugal separation or a part of the necessary quantity may be added at one stage and a part at another stage, so long as the necessary quantity (depending upon the composition of the molasses treated) be added. The invert sugar used in this process may most conveniently be obtained by centrifuging a residual or by-product masse-cuite without the addition of invert sugar, by inverting the molasses removed therefrom and by adding the same as described above to other boiled liquors of the same residual or by-product masse-cuite.

This process for recovering sugar from molasses which is particularly applicable to molasses from sugar cane, may also be applied with advantage to molasses from sugar beets, where this is permitted by the economical and industrial conditions.

Further, it has been found that the inversion of the dissolved sugar in the molasses up to about one third of the said sugar takes place with the greatest of ease and within a short time, whereas the inversion of the remainder of the sugar in the molasses takes place only incompletely and only after a long time. Further, as it is possible by regulating the temperature and time, to obtain any desired degree of inversion of the sugar

in the molasses, therefore it is possible, instead of completely inverting one portion of the molasses or the sugar contained therein, to subject the whole mass of the molasses to inversion until the desired degree of inversion, that is to say until, the required proportion of sugar to invert sugar and salts in the same, is obtained.

Thereafter by a simple regulation of the 10 temperature, the inversion is interrupted. For instance at temperatures below 80° C., the inversion of the sugar in the molasses is immediately arrested to such an extent that a continuation of the inversion even when 15 subsequently boiling the molasses down to masse-cuite cannot be proved to have taken place. The following method of working has proved itself very advantageous in connection herewith.

20 The molasses which has been diluted to a sufficient extent (to about 45° Brix), is strongly acidulated by introducing an acid, while the temperature is being gradually increased to 95° C., and at 95° C. is allowed 25 to stand or is stirred for a shorter or longer period depending upon the required degree of inversion.

As soon as the desired degree of inversion, for instance the inversion of 25% of the 30 sugar in the molasses has been attained, which takes about 5 hours, the inversion is arrested by cooling the mass to a temperature below 80° C.

This cooling is effected immediately on 35 the transference of the partly inverted solution of molasses to the vacuum apparatus, in order to boil the same down to a concentration of masse-cuite.

The boiling of the molasses, so as to convert 40 the same into masse-cuite is carried out at a low temperature and in vacuum, the molasses being treated alone, or in the presence of sugar crystals which promote crystallization.

45 By extracting the sugar from the molasses according to the improved process, it is possible to effect simultaneously a refining or purification of the solution by using suitable inversion agents.

50 The purifying or refining of sugar solutions constitutes an important problem from an economical as well as from a chemi-technical point of view.

A large number of purifying or refining 55 agents have been proposed for sugar solutions, which *per se* possess great purifying properties, such as for instance, aluminum sulfate, mono-calcium phosphate and the like. Such purifying agents, however, when 60 used for working on an industrial scale, do not produce the desired result as an appreciable purifying effect is obtained only by using large quantities of these substances after the alkalis or neutral salts of the sugar 65 solutions have been removed. Under these

conditions, however, besides the purifying effect a strong inversion of the sugar takes place in the solutions, which, however, must be avoided in any case, for which reason the employment of these proposed purifying or 70 refining agents on a large scale has been discarded.

According to a further development of the improved process, however, such agents 75 may be employed, for recovering sugar from molasses, in such quantities that a portion of the sugar is inverted, whereby the same object as described above is attained, and a further recovery of sugar through the great purifying effect, is effected in combination 80 with the inversion.

Although the avoidance of the employment 85 of these measures may be justified in connection with purer sugar solutions from which the sugar is recovered in a crystallized form by simple concentration by evaporation, it is a matter of surprise that these purifying or refining agents may be applied with advantage to the by-product liquids resulting from the manufacture of sugar, 90 *i. e.*, the molasses, as the sugar destroyed in connection therewith by inversion was previously unrecoverable from the molasses, whereas now the inversion of larger amounts of the sugar renders more of the sugar in 95 the molasses recoverable in the form of crystals. The purifying action of the agents employed now no longer effects solely the crystallizing out of the sugar from the molasses, but the invert sugar artificially 100 formed or freshly introduced in the case of sugar cane juices, causes the separation of a further portion of sugar from the solution of molasses in a crystallizable form, and the detrimental effect of the residues of the salts 105 which cannot be removed by the purifying agents is eliminated in consequence of the salting out effect of the invert sugar in impure solutions of sugar. The degree of inversion produced by the purifying agents 110 employed differs, depending upon the nature of the salts in the molasses, and may be practically determined for the various kinds of molasses, so as to obtain the desired proportion of sugar, salts and invert sugar for 115 producing the most favorable results.

Either only one portion of the molasses is treated with the purifying agent and completely inverted, and added to another portion of untreated molasses, or the entire bulk 120 of the molasses is only partially inverted to the desired degree by the purifying agents. The desired degree of inversion of molasses may be easily regulated, no matter 125 what the proportions are, as the salts contained in the molasses exert a preventative protecting effect, and for obtaining an appreciable inversion high temperatures above those required for normal working conditions are necessary, employing, preferably 130

currents of steam of high pressure. When lowering the temperatures below 90° C., or when dispensing with the introduction of steam, an appreciable inversion ceases even during the subsequent boiling in the vacuum apparatus.

Mineral acids for instance, sulfurous acid (SO_2), phosphoric acid and their salts or acid salts, for instance, aluminum sulfate ¹⁰ $Al_2(SO_4)_3$, or mixtures of these are adapted to be used as purifying or refining agents for the molasses for the purpose of effecting a simultaneous inversion of the same.

The following is one form of carrying ¹⁵ into effect the improved process for recovering sugar from molasses:

The molasses is diluted to 45° Brix, heated to a temperature of 100° C., neutralized and for the purpose of effecting the inversion is ²⁰ mixed with a sufficient quantity of a solution of aluminum sulfate or calcium acid phosphate, and thereafter steam from a boiler is introduced into the molasses.

After four to five hours a sufficient inversion ²⁵ (in the case of molasses from sugar cane juices, a sufficient increase in the invert sugar) is produced in addition to the purification. Thereafter the solution of molasses inverted to the desired extent is separated ³⁰ from the precipitated or deposited materials by filtration while in a hot condition.

In cases where the inversion has advanced too far, the solution is adjusted to the desired proportions of sugar, salts and invert sugar by adding untreated molasses to the same. The solution of molasses is concentrated by evaporation in the usual manner, with or without the addition of other sugary ⁴⁰ products of the sugar manufacture, and is allowed to crystallize.

Further it has been found that the invert sugar added to the molasses for the purpose of extracting the sugar therefrom renders ⁴⁵ recoverable a greater quantity of sugar than corresponds to its own weight.

For this reason therefore the process may be modified so that instead of inverting a portion of the sugar contained in the molasses, which heretofore was unrecoverable in a solid form, a corresponding weight of sugar of any origin is inverted. This invert sugar or the invert sugar solution is then added to the whole mass of molasses. ⁵⁰ By means of this expedient the whole process of extracting the sugar from the molasses is considerably simplified, as the inversion of sugar is more economical, more rapid, and more uniform. Further time is saved, and the machinery required is simplified.

The processes described hereinbefore for recovering sugar from molasses by means of inversion may be applied to the molasses ⁶⁵ resulting from the manufacture of beet

sugar as well as to that resulting from the manufacture of cane sugar as well as to the molasses of refineries.

The term "cane sugar" is used in the appended claims to signify sucrose, whether ⁷⁰ obtained from sugar cane, or any other commercial source, and is not intended to be restricted to sugar produced from sugar cane.

I declare that what I claim is:

1. A process of treating cane sugar molasses which comprises effecting the separation, in solid form, of cane sugar from the molasses, by adding to said molasses, an amount of dissolved invert sugar sufficient ⁸⁰ to cause the separation of at least a material proportion of the cane sugar content thereof.

2. A process of separating cane sugar from molasses, which comprises converting ⁸⁵ a portion only of the cane sugar contained in said molasses, into invert sugar, and thereafter allowing contact of said invert sugar and the remaining cane sugar, at a temperature below that at which further amounts of cane sugar would become ⁹⁰ inverted, until at least a portion of the unconverted cane sugar separates from the molasses, in solid form.

3. A process of separating cane sugar ⁹⁵ from molasses, which comprises boiling at least a portion of the molasses with purifying agents capable of inverting cane sugar, until a portion only of the cane sugar of the entire amount of molasses has become inverted, thereafter cooling the so treated portion of said molasses and allowing the separation, in solid form of cane sugar from said molasses.

4. A process of recovering cane sugar ¹⁰⁵ from molasses which comprises dividing the molasses into portions, boiling one portion of the molasses with an acid reagent capable of inverting the bulk of the cane sugar therein, adding the so treated portion of ¹¹⁰ the molasses to another portion of the molasses and causing cane sugar to separate, in solid form, from said molasses.

5. A process of separating cane sugar ¹¹⁵ from molasses which comprises converting a portion of the cane sugar therein into invert sugar, and removing at least a portion of the soluble salts from said molasses, to produce a ratio of cane sugar, invert sugar and salts, favorable to the separation of ¹²⁰ cane sugar from said molasses.

6. In the separation of cane sugar from molasses, the step of salting out cane sugar, from the molasses by the addition thereto of a quantity of invert sugar which is free ¹²⁵ from large quantities of dextrin, and which quantity is sufficient to cause separation in solid form of a considerable proportion of the cane sugar content of the molasses.

7. In the separation of cane sugar, the ¹³⁰

- steps of boiling the molasses with purifying agents capable of inverting a portion of the cane sugar in said molasses, and capable of removing soluble salts from said molasses, lowering the temperature of the molasses to below 80° C., and thereafter separating out solid cane sugar from said molasses.
8. In the recovery of solid cane sugar from molasses, the steps of converting a portion of the cane sugar therein into invert sugar, and removing a portion of the soluble salts, concentrating the molasses at a temperature below 80° C., and separating cane sugar, in solid form, from said molasses.
9. In the treatment of molasses, the step of recovering cane sugar by inverting the sugar content of molasses, and adding the same to other molasses.
- 20 10. A process of treating molasses which comprises subjecting the same to the action of purifying agents in such amounts that there is produced an inversion of a portion

of the dissolved sugar to produce a ratio of sugar, salts and invert sugar, suitable for 25 the separation in solid form of a portion of the contained cane sugar, whereby through the working of the purifying agents as inverting agents, and the salting out action of the produced invert sugar, the production 30 of solid cane sugar from the molasses is effected.

11. In the recovery of sugar from molasses, the herein described improvement which comprises inverting a quantity of 35 cane sugar, and adding the same to the molasses in such proportion as to cause the separation, in solid form, of a large amount of the cane sugar content of the molasses.

In testimony whereof I have affixed my 40 signature, in presence of two witnesses.

FRITZ TIEMANN.
